UNITED STATES PATENT OFFICE.

ROBERT McCLENATHEN, OF FROSTBURG, MARYLAND, ASSIGNOR TO THE KELLY-SPRINGFIELD TIRE COMPANY, OF CUMBERLAND, MARYLAND, A CORPORATION OF NEW JERSEY.

STRIP-FEEDING DEVICE.

Application filed June 22, 1923. Serial No. 647,046.

This invention is particularly adapted to feeding of a flexible strip into or onto an article with which said strip is to become identified, either as a temporary adjunct in 5 an intermediate step in a manufacturing or assembling operation, or, in permanent association therewith.

The preferred embodiment of this invention has been illustrated as a mechanism for 10 inserting flaps into the casings of the conventional open bead automobile tire, but, of course, its application is not limited to this particular operation.

A flap is usually furnished with the tire 15 casing, being inserted therein at the place of manufacture; and the assembled casing containing the flap then suitably wrapped, individually, or in bundles, for shipment. The universal practice followed in inserting flaps 20 is merely the crude hand method, there being no machine device for this purpose. In considering the fact that it is not uncommon for a single factory to turn out upwards of ten thousand casings per day, with flaps inserted by hand, it is apparent that a large 25 number of operatives must be retained to perform this unskilled routine task, and that the expense of this is very considerable.

Having regard to the expense and general 30 inefficiency attending the hand insertion methods it has become the object of my invention to provide a new and novel device for mechanically inserting flaps in tire casings or for performing analogous operations, 35 whereby the operation will be reduced to an efficient and economical basis.

Fig. 1, is a side view of my device, showing 40 a flap being mechanically inserted, and a spare, empty, casing on the feed rack, awaiting its flap insertion.

Fig. 2, is a section through the plane 45 II—II of Fig. 1, showing the chief features of the flap inserting element.

Fig. 3, is a general top view of the entire 50 machine in the plane III—III of Fig. 1.

Fig. 4, is a side view of a portion of the front part of the machine, showing a casing in operating position, and the same (in broken lines) as it is being expelled from the machine upon the completion of the flap inserting process.

Fig. 5, is a sectional elevation in the plane 55 V—V of Fig. 4, showing, particularly, the method of removing the flap inserting ele-

ment from the casing prior to expelling the 55 casing from the machine after the flap has been positioned therein.

Fig. 6, is an enlarged elevation through the guide and traction roller of the flap inserting element, showing the flap being shot into the 60 casing.

The basic conception of the device is that an empty casing is rolled from a suitable 65 source of supply onto a mechanism which automatically centers and retains it in rotation in a vertical plane. While thus retained in a rotating state, an operator threads the end of a flap into the guide of an inserting device,—while that device is in an inoperative position. Next the operator 70 manually swings the inserting device into the casing between the beads; in connection with which movement the inserting device automatically engages moving means (a belt, 75 for instance), just as it reaches a proper relation with the casing, whereby the flap is shot into the casing by the now active inserting device. As soon as the flap is run out of its inserting means into the casing, the operator 80 throws the said means into the inoperative 85 position and quickly expels the casing from the rotating mechanism—the entire operation is thus terminated and ready for repetition.

In view of the simplicity of this device 85 and the clearness of the drawings, which would enable one casually familiar with the art to construct such a machine, only a brief description of details will be introduced 90 herein.

Numerical 1 represents the tray upon which the flaps 2 are stocked in readiness for insertion into the casing 3, one of which (see Fig. 1) is in reserve on the runway 4, the other being in operating condition on the 95 machine.

When inserting a flap, the casing 3 is placed upon two spool drums 5, one of which is direct driven by a motor 6 operating a belt 7 driving a pulley 8 attached to a 100 counter shaft 9. A second pulley 10 on shaft 9 carries a belt 11, which passes over a pulley 12 (see Fig. 3) fast on one of the spindles 13 of the spool drums 5. Having accounted for direct drive of one of the 105 drums 5, it is noted that counterpart pulleys 14 fast on spindles 13 are made to rotate together and in the same direction by a

belt 15, passing over two idlers 16, located midway between the axes of the said spindles and well above them, one over the other. The diameters of the pulleys 14 and 5 their relative axial spacing being such, in relation to the diameter and location of the lower one of the idlers 16, that the belt 15 forms a closing angle toward the idler 16 (the purpose of which will be made apparent).
10

The flap inserting element comprises a shaft 17 having a fixed pulley 18 on one end for rotation purposes and a fixed flap-inserting wheel 19 at the other. The wheel 15 15 19 being spool-shaped and preferably having a rubber friction lining 20 to better draw in the flap 2.

The guide head 21 of the flap inserting element has a rounded portion 22 adapted to 20 facilitate its entrance into and separate the casing beads preparatory to running in the flap; also a slot 23 of U shape is provided to accommodate the normal original form 25 of the flap. Within the head 21 is an idler roll 24, suitably journaled and contacting with the rubber facing 20 on the wheel 19. It being obvious that rotation of 19, when 30 a flap is introduced within the slot 23, will pinch the flap between the facing 20 and the periphery of roll 24 whereby the latter serves as a support and rolling surface for the flap in its passage through the guide head into the casing (see Fig. 6).

The entire flap inserting assembly 35 element may be swung, pendulum-fashion, about a journal 25 suitably bracketed to the main frame of the machine, whereby the head 21 may be forced within the casing at an appropriate time and removed when its 40 work of running in the flap is completed. (See Figs. 4 and 5.) It will become evident that the flap inserting head becomes active when the assembly is swung from the "off" or "up" position toward the tire casing, for the pulley 18 will take motion as it contacts with the two moving portions of the belt 15 (clearly shown in the drawings). A handle 26 is provided to facilitate the operation of this element and a 45 suitable counterbalance arm 27 is provided on the end of the rocking shaft 28 (appropriately associated with the swinging feature of the assembly) whereby the entire moving portion is in approximate balance but tending to remain in the "off" position until manually pulled into the casing.
50

From the foregoing it becomes evident that once a casing is in position on the rotating drums 5, and steadied therein by the pendant idler guide roller 29, all the operator has to do is to pull the free end of a flap from the tray 1, push it partially into the slot 23 of the head 21, then pull down handle 26 whereby the pulley 18 rises within the influence of the belt 15 and the rotat- 60
65

ing elements 19 and 24 within the head grasp and quickly inserts the flap. Thereafter the operator merely throws "off" the element and expels the casing as now described.
70

A pulley 30 (see Figs. 3, 4 and 5) is fixed on shaft 13 and an impeller strap 31 partially surrounds this pulley. One end of this strap is attached to the swinging arm of a casing expeller 32 having an angle portion reaching under the tread of a casing in position on the drums 5, but normally out of contact therewith. This expeller is loosely journaled on the shaft 13 and is unaffected by its rotation. The other end of the strap 31 is attached to an arm of bell crank lever 33, journaled at 34, and carrying on one extremity a contact roller 35 which operates to tighten the belt against the face of pulley 30 when a foot treadle 36 is depressed by the operator. Pressure on 36 operates to pull on a link 37 which in turn rocks lever 33, causing the strap 31 to contract on the pulley 30 whereby the end of the strap attached to expeller 32 is suddenly jerked with the result that the angle portion of the expeller "snaps" sharply up against the tread of the casing (see Fig. 4) displacing it from the drums 5 (as shown in broken lines on Fig. 4). In order that the expeller 32 shall not fall past dead center on the up-stroke, a resilient limit stop 38 of conventional design and balanced by a spring 39 has been provided (the function being clearly indicated in Figs. 1, 4 and 5). With the expulsion of the casing and release of the treadle 36 the belt 31 is slackened and the related mechanism relaxes to the inoperative position.
80
85
90
95

With the mechanism described it is apparent that the operation of inserting flaps is rendered more efficient than the present hand method. In fact, the whole operation is now semi-automatic, absolutely accurate, and the physical exertion on the part of the operator made so slight that unskilled help can be used to advantage; releasing many surplus employees, at present engaged in hand insertion, to higher usefulness.
100

Having now described the preferred embodiment of my device, what I claim is:
115

1. A device of the character described, comprising, means for rotating a tire casing, a common means for locally spreading and mechanically introducing a flap within the said casing, and associated driving means for rotating the casing and operating the flap-introducing means.
120

2. A device of the character described comprising, means for rotating and establishing a definite rotating center for a tire casing, a common means for locally spreading and mechanically introducing a flap within the said casing during a period of rotation, and means for rendering the flap- 125
130

introducing means operative or inoperative at will.

3. A device of the character described comprising, means for rotating a tire casing, means for mechanically introducing a flap within the said casing, and means for expelling the casing beyond the influence of the flap-introducing means.

4. A device of the character described comprising, means for rotating a tire casing in a fixed rotating position, means for mechanically introducing a flap within the said casing, means for rendering the flap-introducing means operative or inoperative at will, and means for mechanically expelling the casing beyond the influence of the flap-introducing means during an inoperative period thereof.

5. In a flap-inserting machine, the combination with means for rotating a tire casing, of a common locally spreading element and mechanical flap-inserter adapted to linearly feed a flap into the rotating casing in the direction of rotation thereof.

25 6. In a flap-inserting machine, the combination with means for rotating a tire casing and means for mechanically expelling said casing at will, of a mechanical flap-inserter adapted to linearly feed a flap into 30 the rotating casing in the direction of rotation thereof, said flap-inserter having means whereby it may be rendered operative or inoperative at will.

7. A device of the character described comprising, in combination, means for positioning an article into which a strip is to be fed, a strip-feeding means adapted to be rendered operative or inoperative at will,

means for attaining relative movement between the article and the strip-feeding means, and means for expelling the article beyond the influence of the strip-feeding means.

8. A device of the character described, comprising a strip-impelling unit having a wedge-like cross sectional contour adapted to enter between and progressively separate the beads of a tire casing, a cross sectionally curved strip guiding slot within said unit, and an impeller element adapted to forcibly feed a strip through said unit.

9. A device of the character described, comprising a strip-impelling unit having a wedge-like cross sectional contour defining its lower side adapted to enter between and progressively separate the beads of a tire casing, a strip guiding and deforming means within said unit defining a cross sectionally curved contour with the apex thereof reversed with respect to that of the wedge-like contour of the said unit, and impelling means associated with said unit for forcibly feeding a guided and deformed strip there through.

10. A device of the character described, comprising a strip-impelling unit adapted to enter between and progressively separate the beads of a tire casing, strip guiding means within said unit, impelling means associated with said unit adapted to feed forward a strip confined within said guiding means, and means for rendering said impelling means operative or inoperative.

In testimony whereof I affix my signature.

ROBERT McCLENATHEN.
